EXTRACTION ELASTIC FLUID TURBINE
ARRANGEMENT

Edgar D. Dickinson, Beverly, Franklin R. Ericson,
Marblehead, and Prescott G. Whittier, Lynn,
Mass., assignors to General Electric Company,
a corporation of New York

Application October 5, 1935, Serial No. 43,794

6 Claims. (Cl. 60—67)

The present invention relates to extraction elastic fluid turbine arrangements; that is, to the type of turbines from which elastic fluid is extracted by means of a conduit connected to an intermediate turbine stage for conducting such fluid to an industrial plant or like apparatus in which available energy of the extracted fluid is consumed. In many cases, such as where the extraction fluid is used for processing purposes, it becomes desirable to supply and consequently extract the extraction fluid at constant pressure or like fixed condition. This is accomplished by the provision of interstage valve means disposed behind the extraction stage, as regards the direction of flow of elastic fluid therethrough. With such valve means, the pressure in the extraction conduit may be maintained constant by closing the valve means in response to a drop in pressure; that is, an increased demand for extraction fluid, and by opening the valve means in response to an increase in pressure of the extraction conduit which may be due to a decrease in demand for extraction fluid.

The object of our invention is to provide an improved construction and arrangement of the type of extraction turbines above specified whereby a condition such as the pressure of the extracted elastic fluid may be readily and accurately controlled.

For a consideration of what we believe to be novel in our invention, attention is directed to the following description and the claims appended thereto in connection with the accompanying drawing.

In the drawing, Fig. 1 represents a sectional view of an extraction turbine embodying our invention; Fig. 2 is an enlarged sectional view of Fig. 1 along line 2—2 of Fig. 1; Fig. 1 being a view along line 1—1 of Fig. 2; and Fig. 3 is a perspective exploded view of certain elements of Figs. 1 and 2.

The arrangement comprises a turbine casing having a lower half 10 and an upper half 11 secured together along a horizontal plane through the turbine center. An intermediate portion of the upper casing half forms a chest 12 which is closed by means including a top plate 13 and a side plate 14. The turbine rotor disposed in the casing, comprises a shaft 15 and a plurality of bucket wheels secured thereto. In the present instance, we have shown a bucket wheel 16 and another wheel 17, the first forming a part of a higher stage, the latter a part of a lower stage. During operation, elastic fluid flowing through 55 the turbine is discharged from the wheel 16 and

conducted to the wheel 17 by means including a diaphragm 18 comprising two halves suitably supported on the outer turbine casing. Not all of the elastic fluid discharged from the higher stage or wheel 16 is conducted to the lower stage of 5 wheel 17, but a part of the fluid discharged from the wheel 16 is extracted through a flanged opening or conduit of 19, the lower casing half; that is, the higher stage with the bucket wheel 16 forms an extraction stage.

Means are provided for controlling the flow of elastic fluid from the higher or extraction stage to the succeeding or lower stage in order to maintain constant a condition of the elastic fluid in the extraction stage; more specifically, in the extraction opening or conduit 19. In the present instance, we have shown means for maintaining constant the extraction pressure. This means comprises, in accordance with our invention, a plurality of substantially balanced valves for controlling the admission of elastic fluid to the lower stage 17, 18. The arrangement shown in the drawing includes eight valves, 20, 21, 22, 23, 24, 25, 26, and 27 (Fig. 1). The valves are arranged in pairs; that is, the valves 20, 21, form one pair, 25 the valves 22, 23 form another pair, etc. and means are provided for consecutively actuating the pairs of valves and the valves of each pair. Thus, during operation the valves may be opened and closed consecutively in the order aforementioned. Each lower valve has a stationary valve casing 28 (Fig. 2) and each upper valve has a stationary casing or body 29. Both these casings are secured to a disc 30 by bolts 31. The disc 30 is split along a horizontal plane 32 (Fig. 1), 35 into two halves united with the diaphragm 18 by means including spacers 33 and welds 34. The provision of the spacers 33 for spacing the valve disc from the diaphragm is important in that it renders the structure more rigid and thus 40 reduces deformation of the diaphragm, the disc 30 and the valves secured thereto. All of the valves are in the form of substantially balanced poppet valves. The lower valves include discs 35 and 36 secured by welds 37 to a hollow valve stem 45 or tube 38 projecting through guides 39 held on the valve casing 28. The upper valves include discs 40 and 41 secured by welds 42 to a hollow valve stem or tube 43 projecting through a guide 44 fastened to the valve casing 29. The hollow 50 valve stems of the lower and upper valves are loosely connected and held in approximate alignment by means of a tube 45 which has a sleeve or thimble 46 secured to its lower end portion and surrounding the upper end portion of the 55

lower hollow valve stem 38 and a sleeve or thimble 47 secured to its upper end portion and surrounding the lower end of the upper hollow valve stem 43. The tube 45, which may be termed an intermediate tube or stem, serves primarily to effect opening movement of the upper valve after the lower valve is at least partially opened. The valves are free to move in their respective bodies. The sleeves or thimbles 46 and 47 form a clearance with the respective ends of the valve stems to introduce flexibility in order to permit the valves to operate freely in case the valve stems go out of alignment due to expansion or deflection of the diaphragm. This is an important feature of our arrangement. As will be noted in Fig. 1, such intermediate tube or stem 45 is provided only with respect to the inner pairs of valves, that is, the valves adjacent the vertical center line of the turbine. Such intermediate tube or stem is not provided with respect to the pairs of valves 20, 21 and 26, 27 because these pairs of valves are close together and arranged so that the stem of the lower valve picks up directly the stem of the upper valve. Valve actuating rod 48 is provided with a key 49 which has an upper spherically shaped surface 50 engaging a spherically shaped surface 51 formed by an inward projection 52 on the lower end of the hollow valve stem 38. From another viewpoint, the lower end of the hollow valve stem 38 is substantially closed to form a key opening 53 through which the key 49 is moved during assembly and disassembly. In operative position, the key 49 is turned by 90° with respect to the opening 53. Locking means are provided for retaining the key in operative position. This locking means includes a tube 54 which has two tongues or locking members 55 and 56 provided at its lower end. These locking members project into the opening 53 after the key 49 has been turned by 90° with respect to the opening 53. During assembly the rod 48 with the key 49 are moved downward through the valve stem 38 until the key 49 has passed the opening 53. Thereafter, the rod 48 is turned by 90° and the locking tube 54 is moved downward until the tongues or locking members 55 and 56 project into or through the key opening 53. In this position, the locking tube 54 prevents relative turning movement between the actuating rod 48 and the valve stems 38 and 43. The retaining or locking tube 54 also forms a lower outer shoulder 57 for positively closing the lower valve. Positive closing of the upper valve is effected by a collar 58 welded to the locking tube 54 above the hollow upper valve stem 43.

The upper end of the actuating rod is connected by means of a flexible coupling 59 to a rod 60 which forms in substance an extension of the rod 48. The mechanism for moving the rod 60 comprises a gear segment 61 supported on a fulcrum 62 and connected to a control or actuating element 63. The segment 61 meshes with a gear 64 secured to a shaft 65. The shaft 65 carries a cam 66 with respect to each pair of valves. Each cam 66 has a surface cooperating with a roller 67 supported on the right-hand end of a lever 68. The left-hand end of the latter is secured to a fulcrum 69 and an intermediate point is provided with a roller 70 engaging an abutment 71 fastened to the upper end of the rod 60. Each rod 60 is surrounded by a compression spring 72 secured at its lower end to a disc 73 on the rod 60 and at its upper end to a stationary plate 75. The compression spring 72 serves to bias the

valve discs towards closing position and to maintain constant contact between the rollers 67 and the corresponding cams 66.

The operation of the mechanism is as follows: If the demand for elastic fluid in the extraction conduit 19 decreases, the regulating or control element 63 is pulled downward to effect counterclockwise turning movement of the gear segment 61. This causes clockwise movement of the gear 64 and the cam 66, whereby the roller 67, together with the right-hand end of the lever 68, is forced upward, causing upward movement of the actuating rods 60 and 48. Upward movement of the rod 48 through the key 49 effects upward movement of the hollow valve stem 38 causing opening of the lower valve discs 35, 36. As soon as the lower valve is opened a predetermined amount, the upper end of the intermediate tube 45 engages the lower end of the upper hollow valve stem 43 so that further upward movement of the valve actuating rod 48 effects opening movement of the upper valve discs 40 and 41. Similarly, during closing movement, the rods 60 and 48 are moved downwardly by the action of the compression spring 72 and the weight of the movable valve members. During downward movement of the valve actuating rod 48 the valves are also closed in succession. At first the upper valve is closed and thereafter the lower valve. Closing is aided by the elastic fluid pressure due to the fact that each poppet valve is slightly unbalanced so that the pressure of elastic fluid tends to move the valve discs downward towards closing position. As will be readily seen in the drawing, the upper discs 35 and 41 of each valve are slightly larger in area than the lower discs 36 and 40, whereby the difference in pressure between the outside of the valve bodies 28 and 29 and within said valve bodies assures tight closing of the valves.

Having described the method of operation of our invention, together with the apparatus which we now consider to represent the best embodiment thereof, we desire to have it understood that the apparatus shown is only illustrative and that the invention may be carried out by other means.

What we claim as new and desire to secure by Letters Patent of the United States is:

1. An extraction elastic fluid turbine arrangement including the combination of a turbine casing, a rotor having a plurality of bucket wheels disposed in the casing to form a plurality of consecutive stages, means for extracting elastic fluid from an intermediate stage, a diaphragm for directing the flow of elastic fluid within the casing from the extraction stage to the succeeding bucket wheel and means for controlling the flow of elastic fluid to the diaphragm in order to maintain constant a condition of the extracted fluid, said means comprising a disk disposed ahead of the diaphragm as regards the direction of flow of fluid, spacing means intermediate the diaphragm and the disk supporting the disk on the diaphragm and reducing deformations of the diaphragm and the disk, a plurality of pairs of valves for controlling the flow through said openings and means for consecutively moving the pairs of valves.

2. An extraction elastic fluid turbine arrangement including the combination of a casing, a rotor in the casing forming a higher stage and a lower stage, means for extracting elastic fluid from the higher stage and means for controlling the flow of elastic fluid from the higher stage to

the lower stage to maintain constant a condition of the extracted fluid, said means comprising a disk having a plurality of upper and lower openings disposed between the higher stage and the lower stage and supported on the casing, and valve means for controlling the flow of elastic fluid through the openings, said valve means being arranged in pairs, each pair including an upper and a lower valve body fastened to the disk, a substantially balanced valve member including a hollow valve stem for each body and means for effecting consecutive movement of the valve stems.

3. An extraction elastic fluid turbine arrangement including the combination of a casing, means disposed within the casing forming an extraction stage and a succeeding stage, a disk located intermediate the two stages and supported on the casing, said disk having two openings vertically above each other, an upper and a lower valve, each valve including a body secured to the disk and a substantially balanced valve member having a hollow stem to control the flow from the extraction stage through the disk openings to the succeeding stage, means aligning the hollow valve stems of the two valves and to effect consecutive movement of the two valves comprising an intermediate hollow stem having an upper sleeve surrounding the lower end of the upper hollow stem and a lower sleeve surrounding the upper end of the lower hollow stem, and means for moving the valves comprising an actuating rod concentrically disposed within the hollow valve stems and including a key secured to its lower end for engaging the lower end of the lower hollow valve stem.

4. An extraction elastic fluid turbine arrangement including the combination of a casing, means disposed within the casing forming an extraction stage and a succeeding stage, a disc having two openings vertically above each other being disposed intermediate the stages, an upper and a lower valve for controlling the flow of fluid through said openings, each valve including a body secured to the disc and a substantially balanced valve member having a hollow stem, means for effecting consecutive movement of the two valves comprising an intermediate hollow stem engaging the adjacent ends of the hollow stems, means for moving the valves comprising an actuating rod concentrically disposed within the hollow valve stems and having a key secured to its lower end for engaging the lower end of

the lower hollow valve stem, and locking means to prevent relative rotary movement between the actuating rod and the lower valve stem.

5. An extraction elastic fluid turbine arrangement including the combination of a casing, means disposed within the casing forming an extraction stage and a succeeding stage, a disc having upper and lower openings vertically above each other being disposed between the stages and supported on the casing, means including an upper and a lower valve for controlling the flow of elastic fluid through the openings, each valve including a body secured to the disc and a valve member with a hollow stem, means aligning the hollow valve stems and effecting consecutive movement of the two valves comprising an intermediate stem engaging the upper and the lower valve stems, and means for moving the valve members comprising an actuating rod concentrically disposed within the hollow valve stems and having a key secured to its lower end in cooperative relation with the lower hollow valve stem, a locking tube surrounding the actuating rod for preventing relative rotary movement between the actuating rod and the lower valve stem and a collar secured to an upper portion of the locking tube to effect positive closing of the upper valve.

6. An extraction elastic fluid turbine arrangement including the combination of a casing, a higher stage and a lower stage including a diaphragm formed in the casing, an extraction conduit connected between the higher stage and the lower stage, and means for controlling the condition of elastic fluid in the extraction conduit comprising a disc having an upper and a lower opening and disposed ahead of the diaphragm as regards the direction of flow of elastic fluid, means for spacing the disc from and securing it to the diaphragm, and means for controlling the flow of elastic fluid through said openings comprising an upper valve and a lower valve, each valve having a valve stem, and means loosely connected between the valve stems to permit opening of one valve after the other valve has been at least partially opened, said last named means permitting flexibility between the valves and free movement thereof during expansion and deflection of the diaphragm.
